CIGARETTE CASE

Max E. Bernhardt, New York, N. Y.

Application November 23, 1933, Serial No. 699,364

5 Claims. (Cl. 206—41)

This invention has general reference to cigarette cases or containers for analogous articles and has to do with cases or containers of the type in which the articles contained therein are urged 5 by a spring pressed follower to a predetermined position and in which the case or container is made up of a pair of mating sections which are associated for relative movement to an open relation for filling the same or emplacing the articles therein.

The invention broadly comprehends means for effecting the retraction of the follower upon relative movement of the casing sections to their open relation.

The invention further resides in the provision 15 of means on the follower and on one of the casing sections respectively, which means are so constructed and arranged as to automatically engage and effect the retraction of the follower upon relative movement of the casing sections to open 20 relation, thereby disposing the follower in an out-of-the-way position and facilitating the emplacement of the cigarettes or other contents within the case.

The invention also has relation to cigarette 25 cases or containers of the character set forth which include means for dispensing the articles or cigarettes, together with a spring urged follower for advancing the articles or cigarettes to a position to be dispensed and in which the case 30 includes sections which are associated for relative movement to open relation so as to permit of the filling thereof and which casing sections, upon relative movement, actuate the dispensing means.

The invention furthermore, includes in combination with containers or cases of the character 35 set forth, detent means for temporarily holding the follower in retraced position against the action of its spring and which detent means may be releasable through the medium of the interengaging follower retracting means, upon initial movement of the casing sections to closed relation.

The invention further embodies interengaging 45 follower retracting means provided respectively on the follower and on one of the casing sections, which retracting means are disengaged, after the emplacement of the contents, by the arresting of the movement of the follower through the medium of the contents.

The invention further provides an improvement 50 in cigarette cases or similar containers which is extremely simple in its construction and mode of operation and which may be inexpensively produced and incorporated in the case or con-

tainer structure, while greatly adding to the efficiency thereof.

With the above enumerated and other objects and advantages in view, reference is now had to the specification and drawing in which there has been illustrated, by way of example, one embodiment of the invention, while the claims cover variations and modifications thereof which fall within their range and scope.

In the drawing,

Fig. 1 is a front view of the body section of the case with the cover section removed.

Fig. 2 is an inner face view of the cover section.

Fig. 3 is an enlarged vertical sectional view 15 through the case taken approximately on the line 3—3 of Fig. 1 and illustrating the follower engaged and partially retracted by the cover section.

Fig. 4 is a similar view illustrating the follower 20 in fully retracted position, with the detent means engaged for temporarily holding the follower in retracted position.

In the present disclosure, the invention includes 25 a cigarette case which comprises a body section designated generally by the reference character A and a cover section designated generally by the reference character B, which sections are slidably associated for relative movement from a closed to an opened relation for filling the same.

The body section A includes a rear wall 5, side 30 walls 6 and 7, and upper and lower end walls 8 and 9 which are preferably formed integral with the rear wall. The end walls 8 and 9 have front wall portions 10 and 11 directed inwardly towards 35 each other and spaced from each other and from the rear wall 5. The side wall 6 terminates in spaced relation to the upper end wall 8 to define therewith a dispensing opening 12 through which the cigarettes are adapted to be ejected and dis- 40 pensed.

A longitudinally extending front wall section 13 extends inwardly from the forward edge of the side wall 7 and the free edges of the front wall portions 10, 11 and 13, and the forward edge of 45 the side wall 6, define a filling opening 14 in the front of the body section for gaining access to the interior thereof in order to introduce the cigarettes.

The cover section B includes a front wall 15 50 and preferably integral rearwardly directed side walls 16 and 17, the inner surfaces of which are spaced apart appropriate distance so as to snugly fit over the outer surface of the side walls 6 and 7 of the body section. The rear edges of the side 55

walls 16 and 17 are provided with inwardly directed flanges 18 and 19 by virtue of which the cover section is longitudinally slidable with reference to the body section, so that said cover section 5 may be moved to opened and closed relation and when opened, uncovers the filling opening 14 at the front of the body section, so that the cigarettes may be introduced therethrough.

In the particular form of the case disclosed, a 10 dispensing mechanism is provided, which includes a resilient ejector arm 20, anchored at one of its ends to the front wall portion 13, as at 21, and which ejector arm is provided with an ejector terminal 22 and has a cam portion 23 adjacent said 15 terminal. The cover section is provided on its inner or rear face with an actuating lug 24 which is designed to engage the cam portion 23 of the ejector arm to effect the retraction of the ejector terminal 22 upon closing movement of the cover 20 section B and to permit of the ejector arm to partially eject the endmost cigarette when the cover section is moved towards open relation.

The body section A may be of a size to receive 25 and accommodate any desired number of cigarettes which are transversely disposed in contiguous parallel relation in a single row between the end wall 8 and a spring actuated follower 25, which follower functions to shift the cigarettes into position to be acted upon by the ejector terminal 22 which lies behind the innermost end of the endmost cigarette for engaging and axially moving the same to the partially ejected position 30 illustrated in Fig. 1.

The follower 25 includes an upper wall 26 having 35 marginal rearwardly directed side and end walls 27 and 28. The follower 25 is urged towards the upper end wall 8 by a spring 29, the upper end of the spring engaging the underside of the upper wall 26 and lying between the walls 27 and 28, 40 while the lower end of said spring bears against the lower end wall 9 of the body section A.

In order to provide means for effecting the retraction of the follower upon opening movement 45 of the cover section B, an element 30 is provided on the cover section and is adapted to automatically engage with the follower to move the same therewith to retracted position against the action of the spring 29 so that, as illustrated in Fig. 4, the follower is disposed in an out-of-the-way position, leaving the filling opening 14 at the front of the body section clear and unobstructed, for introducing the cigarettes therethrough and 50 emplacing the same within the body section A.

As disclosed in the particular form of the 55 invention selected for the purpose of illustration, the element 30 is in the form of a knob which protrudes inwardly or rearwardly from the inner or rear face of the front wall 15 of the cover section, adjacent its upper edge. Preferably, although not necessarily, the follower is provided with an element 31 with which the element 30 on the cover section engages and which element, as particularly illustrated, is in the form of a forwardly protruding finger cut and bent from the 60 forward side wall 27 of the follower.

In practice, the side walls 16 and 17 of the cover 70 section B may frictionally engage with the body section with sufficient force to retain the cover and follower in retracted position against the action of the follower spring 29 but if this frictional engagement is not desired, detent means may be provided for the purpose of holding the follower in fully retracted position. As illustrated, the 75 detent means includes a spring latch 32 carried by the follower, and a keeper 33 carried by the body

section. As specifically shown, the spring latch is in the form of a split resilient ring which is anchored to the forwardly protruding finger 31 and disposed in flat contact with the forward side wall 27 so that the portion of the ring above the finger 31, together with the finger, defines a knob receiving socket 34 into which the knob 30 snaps when the cover section B is moved towards the open position. The ends of the split ring are formed with downwardly divergent terminals 35 which terminals, due to the inherent resiliency of the split ring, are normally in contact at their juncture with the ring ends, and thus provide means for engagement with the keeper 33, which keeper is in the form of an inwardly directed 10 finger formed in the notched portion 36 of the upper edge of the front wall portion 11 of the body section.

In operation, when the cover section B is moved to open position and the knob 30 snaps into the 15 socket 34, the subsequent opening movement of the cover section retracts the follower to the position illustrated in Fig. 4 where the divergent terminals 35 of the spring latch or split ring engage with the keeper 33 and are cammed and 20 spread apart to engage below and behind the keeper. The follower is thus detained temporarily in its out-of-the-way position, while the articles or cigarettes are being introduced into the body section of the case. After the case has been filled, 25 the initial closing movement of the cover section B, through the engagement of the knob 30 with the upper portion of the split ring which defines the socket 34, effects the release of the split ring from the keeper 33 whereby the follower is free to 30 be moved upwardly by the follower spring 29. The continued upward movement of the cover section B causes the knob 30 to be disengaged from the socket 34, due to the fact that the follower will be arrested by the cigarettes or articles C. 35 The cover thus released may be moved to the fully closed position illustrated in dotted lines in Fig. 4, and the follower, urged by the spring, 40 functions to move the cigarettes into dispensing position in alignment with the dispensing opening 12.

The front wall portion 10 is provided with notches 37 and 38 which open through and extend from the lower edge thereof to afford clearance for the movement of the actuating lug 24 and knob 30 and finger 31. The front wall portion 11 is notched at 39 to also afford clearance for the actuating lug 24 when the cover is fully 45 retracted.

From the foregoing it will be observed that the 50 cover section in addition to serving as a closure for the body section, also functions in the several capacities, namely, as an actuating means for the dispensing of the cigarettes, as a means for retracting the follower and as a means for releasing holding means for the follower if such a means is employed.

What is claimed is:

1. In a cigarette case, including a body section and a cover section associated therewith for relative movement to opened and closed relation, means on the body section for dispensing the cigarettes, means on the cover section for actuating the dispensing means upon relative movement of the cover section, a spring urged 65 follower for moving the cigarettes to dispensing position and means carried by the cover section for retracting the follower upon relative movement of the cover section to open position.
2. The combination with a container for cig- 75
